UNITED STATES PATENT OFFICE.

HERBERT HAMPTON, OF KINDER, LOUISIANA, ASSIGNOR OF ONE-HALF TO CHAS. F. HOWELL, OF KINDER, LOUISIANA.

BROOM-HEAD.

1,069,873.

Specification of Letters Patent. Patented Aug. 12, 1913.

Application filed September 25, 1912. Serial No. 722,331.

To all whom it may concern:

Be it known that I, HERBERT HAMPTON, a citizen of the United States, residing at Kinder, in the parish of Calcasieu, State of 5 Louisiana, have invented certain new and useful Improvements in Broom-Heads; and I do hereby declare the following to be a full, clear, and exact description of the invention, such as will enable others skilled in 10 the art to which it appertains to make and use the same.

This invention relates to new and useful improvements in broom heads, and more particularly to one so constructed that the 15 broom may be conveniently removed when worn and replaced by a new one.

The invention has for its object to provide a broom head constructed in such a manner that the broom will be held in place 20 therein by clamping members which may be easily manipulated to remove the broom from the head.

With these and other objects in view, this invention resides in the novel features of 25 construction, combinations and arrangements of parts to be hereinafter more fully described, claimed and illustrated in the accompanying drawing, in which:—

Figure 1 is a front elevation of the device. Fig. 2 is a rear elevation. Fig. 3 is a side elevation. Fig. 4 is a sectional view on line 4—4 of Fig. 1. Fig. 5 is a similar view on line 5—5 of Fig. 1. Fig. 6 is a similar view on line 6—6 of Fig. 1.

Referring to the drawing, the numeral 1 35 designates a handle, which may be of the usual construction and has its lower end secured in a ferrule 2 formed upon the upper end of the rectangular casing 3, said casing being formed from suitable metal. A pair of vertically disposed arms 4 are 40 provided, and are connected at their upper ends by a bar 5 which passes through an opening in the handle 1, the lower ends of said arms are provided with lateral extensions 6 which are engaged in the opposite 45 ends of a clamp plate 7, said plate being provided with a plurality of aligned perforations 8 which extend longitudinally of

the plate, the purpose of which will appear 50 later. The arms 4 are provided intermediate their ends with shoulders 9, which are engaged by coils 10 which form a continuation of the upper ends of the arms 11, said coils terminating at their inner ends in a 55 yoke 12 which bears against the lower end of the handle 1. The arms 11 are substantially the same length as the arms 4, and have their lower ends formed with hooks 13 which engage the perforations 14 formed 60 in the opposite ends of the plate 15. The inner surface of the plate 15 is provided with a plurality of horizontally aligned spurs 16 which are adapted to engage the perforations 8 carried in the clamping plate 65 7, after said spurs have passed through the broom straw 17 forming the broom proper. A bow 17' is provided and has its ends connected to the bar 5, and in conjunction with the yoke 12 holds the device against lateral 70 movement in respect to the handle 1. The straws forming the broom 17 are secured together at their upper ends by a canvas or other suitable fabric casing.

From this construction it will be seen 75 that the broom 17 may be readily replaced in the casing 3, and upon forcing the arm 7 outwardly the plate 15 will be moved sufficiently away from the plate 7 to permit the broom to pass between the said plate, whereupon when the arms are released the spurs 80 16 will pass through the broom jaws and engage in the perforations 8, thereby securely holding the broom in place.

What is claimed is:—

In a broom head, the combination with a handle, of a casing secured to the lower end of the handle, a pair of spaced vertical arms connected at their upper ends by a bar which passes through said handle, shoulders 90 formed intermediate the ends of said arms, lateral extensions formed upon the lower ends of the arms, a clamping plate having its opposite ends secured to the extensions, and provided with perforations, a second 95 pair of arms having their upper ends terminating in coils encircling said shoulders of the first named arms, said coils terminating

at their inner ends in a yoke bearing against the handle, hooks formed upon the lower ends of the second named arms, a plate connected to said arms by the hooks, spurs 5 secured upon the inner face of said plate and adapted to pass through a broom when the upper end thereof is engaged in the casing, said spurs being adapted to engage

the perforations of the clamping plate, as and for the purpose set forth. 16

In testimony whereof, I affix my signature, in presence of two witnesses.

HERBERT HAMPTON.
